US0D1072561S

(12) **United States Design Patent** (10) **Patent No.:** **US D1,072,561 S**
(45) **Date of Patent:** **** Apr. 29, 2025**

(54) **LID**

(71) Applicant: **Foshan Jiuzhou Technology Co., Ltd.**,
Guangdong (CN)

(72) Inventor: **Wei Yu**, Guangdong (CN)

(73) Assignee: **Foshan Jiuzhou Technology Co., Ltd.**,
Guangdong (CN)

(**) Term: **15 Years**

(21) Appl. No.: **29/964,920**

(22) Filed: **Sep. 25, 2024**

(30) **Foreign Application Priority Data**

Aug. 6, 2024 (CN) 202430496299.9

(57) **CLAIM**

The ornamental design for a lid, as shown and described.

DESCRIPTION

FIG. 1 is a front, right, top perspective view of a lid, showing my new design;

FIG. 2 is a rear, left, bottom perspective view thereof;

FIG. 3 is a front elevation view thereof, shown in a reduced scale;

FIG. 4 is a rear elevation view thereof, shown in a reduced scale;

FIG. 5 is a left side view thereof, shown in an enlarged scale;

FIG. 6 is a right side view thereof, shown in enlarged scale;

FIG. 7 is a top plan view thereof; and,

FIG. 8 is a bottom plan view thereof.

The broken lines in the drawings are for the purposes of illustrating portions of the lid that form no part of the claimed design.

1 Claim, 8 Drawing Sheets
